PUMP FOR ELEVATING LIQUID

Filed Feb. 24, 1925

FIG. I

UNITED STATES PATENT OFFICE

WILLIAM F. LESCHEN, OF ST. LOUIS, MISSOURI.

PUMP FOR ELEVATING LIQUID

Application filed February 24, 1925. Serial No. 11,144.

This invention relates generally to pumps for elevating liquids, and particularly to a pump for pumping liquid, especially oil, from below the ground.

As is well known, oil wells are usually quite deep, said wells frequently being thousands of feet in depth, and prior to this invention the pumps used in oil wells usually each comprised a plunger arranged to reciprocate in a cylinder, which plunger was attached to the lower end of a rod or plurality of rods extending from above the ground. The plunger reciprocated at a point relatively close to the bottom of the well, and because of this fact the rod to which said plunger was attached was of very great length. The purpose of the present invention is to produce a pump of the type mentioned which is so constructed and arranged that the length of the rod to which the reciprocating plunger is attached is greatly reduced, thereby reducing the initial cost of the rod and also reducing the power necessary to reciprocate said rod and the plunger because of the lessened weight of said rod.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a vertical section of the lower portion of my improved pump.

Fig. II is an enlarged fragmentary vertical section of the lower end of the pump illustrated in Fig. I.

Fig. III is a cross section on line III—III of Fig. II.

In the drawing, A designates my improved pump, which comprises an outer tubing 1 and an inner tubing 2. The outer tubing 1 has a reduced portion 3, said reduced portion being connected to the larger upper portion of said tubing by means of a horizontal wall 4. The inner tubing 2 is of less diameter

than the outer tubing 1, so that an annular space 5 is provided between the walls of said outer tubing and said inner tubing. By referring to Figs. I and II it will be seen that the lower end of the inner tubing 2 is spaced apart in a vertical direction from the horizontal wall 4 to provide a space 6.

Located within the inner tubing 2 is a plunger 7 which is attached to the lower end of a sucker rod 8. The plunger 7 is of a type which has been in use for some time, said plunger being provided with a central longitudinal opening 9 which is normally closed at its upper end by a ball valve 10, said ball valve being located within a cage 11 to retain same in its proper position relative to the upper end of the opening 9. The plunger 7, as will be seen by referring to Fig. II, is provided with the usual packing rings 12 to insure fluid-tight contact between the peripheral face of said plunger and the wall of the inner tubing 2. The upper end of the sucker rod 8 is connected to a suitable mechanism which is located above the ground and which imparts reciprocating motion to said rod and to the plunger attached thereto.

Arranged at a point adjacent to the lower end of the pump A is a member 13. The member 13 is circular in cross section and comprises an enlarged head portion 14 and a reduced stem portion 15. As shown clearly in Figs. I and II, the head portion 14 of the member 13 is arranged within the inner tubing 2, and said head portion is adapted to reciprocate within said inner tubing. To provide fluid-tight contact between said head portion of the member 13 and the wall of the inner tubing, I employ packing rings 16. The stem portion 15 of the member 13 extends downwardly from the head portion 14 thereof into the reduced portion 3 of the outer tubing 1, said stem portion 15 being of such diameter that it may be reciprocated within said reduced portion 3. To provide fluid-tight contact between the stem portion 15 and the inner face of the wall of the reduced portion 3 I employ packing rings 17. Extended through the member 13 is a central longitudinal opening 18, which is normally closed at its upper end by a ball valve 19, said

ball valve being arranged within a cage 20 so that it will be retained in its proper position relative to the upper end of the opening 18.

The reduced portion 3 of the outer tubing 5 is provided with a comparatively thick bottom wall 21 which has an opening 22 formed therethrough. Arranged at the upper end of the opening 22 and adapted to normally close said opening is a ball valve 23, there being a cage 24 provided to retain said ball valve in its proper position relative to the upper end of said opening.

Prior to placing my improved pump in operation, liquid, for instance oil, is poured into the annular space 5 between the tubings 1 and 2, this space 5, together with the space 6, being filled to the desired level, and also liquid is poured into the inner tubing 2. Assume now that the pump has been in operation and that the parts thereof are in the positions in which they are shown in Fig. I. The plunger 7 is reciprocated by the mechanism above the ground, and on each upward stroke of said plunger a portion of that body of oil 25 which is located above the plunger will be discharged from the pump. It will be noted that on the upward stroke of the plunger the ball valve 10 associated with said plunger is closed.

Confined between the plunger 7 and the upper end of the member 13 is a body of oil which is designated by the reference character X. Located in the spaces 5 and 6 and in the inner tubing 2 below the head 14 of the member 13 is a body of liquid already referred to, which will now be designated by the reference character Y. It will be noted that the body of liquid within the inner tubing 2 and above the member 13 rests upon the top face 40 14^a of the head 14 of said member 13, and it will also be noted that the body of liquid Y contacts with the lower face 14^b of said head 14.

The height of the body of liquid Y in the space 5 may be approximately the same as the height of the entire body of liquid within the inner tubing 2 above the face 14^a of the head 14. In other words, when the valve 10 associated with the plunger 7 is unseated and the liquid within the inner tubing above the head 14 is in the form of a continuous body which extends from the face 14^a of said head 14 to the top of the pump, this body of liquid is approximately the same height as the body 50 55 of liquid Y. The area of the face 14^a of the head 14 is much greater than the area of the face 14^b of said head, and the first thought would be that because of this greater area the total downward pressure of the liquid within the inner tubing acting on the member 13 60 would be greatly in excess of the total upward pressure of the liquid acting on said member 13. This, however, is not the case for the reason that there is a body of liquid Z in 65 the reduced portion 3 of the outer tubing with

which the face 14^c at the lower end of the stem portion 15 of the member 13 contacts, and while downward pressure is exerted against the whole face 14^a by the body of liquid above said face 14^a, upward pressure 70 is exerted against the face 14^c by the liquid Z below said face 14^c. The result of this is that in calculating the effective area of the face 14^a the area of the face 14^c must be subtracted from the total area of the face 14^a, 75 and when this is done it will be found that the effective area of the face 14^a is approximately the same as the area of the face 14^b. It is apparent, therefore, that the pressure per square inch exerted by the entire body of 80 liquid within the inner tubing 2 above the face 14^a against said face 14^a on the downward stroke is approximately the same as the pressure per square inch exerted by the body of liquid Y against the face 14^b.

It has already been stated that on each upward stroke of the plunger 7 some of the liquid within the inner tubing 2 above the plunger 7 will be discharged from the pump. It is apparent that if some means were not provided to cause the body of liquid X to move with the plunger 7 when said plunger moved upwardly, said plunger would move away from said body of liquid X, which at this time has been separated from the liquid above the plunger by the closing of the valve 10. In other words, the body of liquid within the inner tubing 2 would be divided into an upper body, or that liquid which is above the plunger 7, and a lower body, or that liquid which is below the plunger 7. It is plain, therefore, that when the plunger moves upwardly and the valve 10 closes a column of liquid X would be provided which is of much less height than the body of liquid Y, and consequently the pressure per square inch of the body of liquid Y at the face 14^b would be greatly in excess of the pressure per square inch of the liquid X at the face 14^a.

In view of the foregoing it is quite apparent that as the plunger 7 moves upwardly the pressure of the body of liquid Y would exert an upward force against the lower face 14^b of the head 14, and because the pressure per square inch of the body of liquid Y at the face 14^b multiplied by the area of said face 14^b is greatly in excess of the pressure per square inch of the body of liquid X at the face 14^a multiplied by the area of said face 14^a the member 13 would be elevated, 110 and as the valve 19 would be closed at this time it is plain that the body of liquid X would be lifted by said member 13. When the member 13 is elevated as described, it is plain that suction would be created in the 115 reduced portion 3 of the outer tubing 1, which suction would have the effect of unseating the ball valve 23 and drawing the liquid through the opening 22.

The action of the pump on the upward 120 125 130

stroke has been explained, and it will be assumed now that the plunger 7 is at the top of its stroke and is just starting downwardly. On the downward stroke of the plunger 7 the valve 10 is unseated by the passage of liquid through the opening 9 in said plunger, and this will have the effect of reuniting the separated portions of the body of liquid within the inner tubing 2 above the member 13. In other words, a complete column of liquid which extends from the face 14^a of the member 13 to the top of the pump will be provided. As has already been stated, the height of this column of liquid is approximately the same as the height of the body of liquid Y, and because the faces 14^a and 14^b have approximately the same effective areas there will be a balance of power, the downward pressure exerted against the face 14^a being approximately the same as the upward pressure exerted against the face 14^b. However, the member 13 is of considerable length and consequently of some weight, and because the pressure all around said member 13 will be approximately equal said member will move downwardly by gravity, and this downward movement of the member 13, added to the downward pressure of the body of liquid within the tubing 2 above the member 13, will be sufficient to overcome the upward pressure of the body of liquid Y against the member 13, and because of this excess of power in a downward direction the body of liquid Y will be forced upwardly in the space 5. When the member 13 is moving downwardly the valve 19 is unseated to permit liquid which was below the member 13 to be added to the body of liquid X above said member. It is plain, therefore, that a reciprocating pump is provided the plunger of which operates many feet above the bottom of the well, and this is accomplished by dividing a body of liquid into an upper body and a lower body, said upper body being raised by the plunger of the pump and the lower body being raised to the position occupied by the plunger of the pump by an auxiliary body of liquid, said separated bodies of liquid being reunited to provide sufficient force to return said auxiliary body of liquid to its normal position after it has performed its function of raising one of said bodies of liquid.

To provide for the escape of gas which may accumulate within the reduced portion 3 below the face 14^c of the member 13, I form an elongated opening 27 adjacent to the lower end of the stem portion of said member 13. This opening is so arranged that at the upper end of each stroke of the member 13 a portion of said elongated opening will be above the horizontal wall 4 and a portion thereof below said horizontal wall. In this way communication is obtained between the interior of the reduced portion 3 and the space 6 which will permit any gas which may be within said reduced portion to pass into said space 6 and bubble upwardly through the liquid in the space 5 and escape at the top of the pump.

While I have stated in this specification that the height of the column of liquid within the inner tubing 2 and the height of the column of liquid Y are approximately the same, I did this to simplify the description of the invention. However, I desire it to be understood that it is not necessary that said columns of liquid be the same height, but their heights and pressures may vary without interfering with the successful operation of the invention.

I claim:

1. A pump for raising fluids from great depths, comprising an outer casing adapted to extend from the level of the liquid upwardly to a point substantially adjacent to the outlet of the well, an inner casing arranged in concentric relation with respect to the outer casing having its lower end terminating above the extremity of the outer casing, and a plurality of independently arranged plungers located within the inner casing, said plungers being so constructed and arranged that movement imparted to one of the plungers to draw upwardly liquid located above the plunger will result in upward movement being imparted to the lower plunger by means of liquid in the outer casing working on the under face of the lower plunger.

2. A pump for elevating liquids from great depths, comprising an outer casing arranged to extend from the ground level to the fluid level of the well, an inner casing located substantially concentric with respect to the outer casing and arranged to extend downwardly and to terminate above the lower extremity of the outer casing, means closing the lower extremity of the outer casing, said means comprising a plunger adapted to move within the inner casing, and a second plunger mounted in the inner casing and separated from and independent of the first plunger, the plungers being so constructed and arranged that movement imparted to the upper plunger when the pump is full of liquid results in movement being imparted to the lower plunger by means of liquid in the outer casing working on the under face of the lower plunger.

In testimony that I claim the foregoing I hereunto affix my signature.

WILLIAM F. LESCHEN.
